UNITED STATES PATENT OFFICE.

ROBERT A. GALLY, OF CINCINNATI, OHIO, ASSIGNOR TO THE BALDWIN COMPANY, OF CINCINNATI, OHIO.

MUSIC-PLAYING-SHEET INDICATION.

1,246,413.

Specification of Letters Patent. Patented Nov. 13, 1917.

Application filed September 22, 1914. Serial No. 862,937.

To all whom it may concern:

Be it known that I, ROBERT A. GALLY, a citizen of the United States, residing at Cincinnati, in the county of Hamilton and State 5 of Ohio, have invented certain new and useful Improvements in Music-Playing-Sheet Indications, of which the following is a specification.

Previous forms of marking the words of 10 a song, or directions for playing, on a perforated or other music sheet adapted to control the playing of a self-playing musical instrument or attachment, have had such words, syllables, letters or signs arranged 15 with the vertical dimensions of the letters or characters lying in the direction of travel of the sheet and each word, syllable, character or combination of letters disposed with their reading alinement or transverse dimension in direction at right angles to said 20 line of travel. Such disposition of characters has been difficult to read, especially when such sheet is moving rapidly during playing, and it has also required extra lines or 25 designations to determine the duration of the syllables of the words of a song.

All of these drawbacks are now overcome by the diagonal, slanted, or stepped arrangement of the characters on the music sheet 30 of the present invention. The use of the slotted perforations for the notes of the melody or theme and grouped hole series perforations for the accompaniment notes or subordinate musical parts or voices as 35 now shown, aids the following of the melody, but is not claimed, as same was old in the art with M. Gally, Re- #8,856, August 19, 1879 and #329,304, October 27, 1885.

The drawing shows a perforated music 40 sheet having note perforations and graphic characters according to the present invention.

The music sheet 1 has note perforations 2 and 3, preferably the melody or theme 45 note perforations 2 being of a continuous slot to each note, and the accompaniment or secondary note perforations 3 being of a series of small perforations grouped together for each such note, although both 50 melody and accompaniment may be all slotted, or any other form. While this is the simplest and clearest manner of distinguishing the melody or leading part from the accompaniment or secondary parts, the desired differentiation may be accomplished 55

by the reverse use of slots and series groups, by different widths or shapes of perforations, or other suitable means, and be useful with the words or other character designations herein set forth, or these words or 60 character designations may be applied to a sheet having all its perforations of one style.

The opening words of the song "Anchored" are shown applied to the music sheet 1, arranged in successive rows or 65 groups on a slant to the line of travel of the sheet, which direction of travel is designated by the arrow. Such words are preferably grouped so that each clause or phrase of the verse is comprised in one group. 70 Each word, syllable or character, preferably has its commencement at a position in transverse alinement with the commencement or first end of the melody or theme note perforation 2 with which it is to be sung, or to 75 which it relates, the melody and accompaniment notes being preferably of different styles of perforations to aid the distinguishing of the pitch and duration of the melody note. Various expression words or characters may be similarly positioned at a slant 80 to said line of travel, as shown by the word "Softly", the numeral "70" and the characters "PP", and such words or characters in such angle position may relate to either 85 the melody or secondary notes, or to the general character or rendering of the music.

The slanting arrangement of words, etc., may also be used on a sheet where only the accompaniment is included, the melody not 90 being perforated or shown, as at upper part of the music sheet, or only the accompaniment perforated and the melody shown by marks or lines as 4. The use of a sheet with some of the musical parts perforated therein, and other musical parts or voices graphically indicated, is old in my previous Patent 95 #749,181, January 12, 1904.

It is understood that the words, syllables, or characters may be applied to the sheet by 100 printing, stamping, stenciling, or any other means of producing graphic indications.

What I claim as my invention is:—

1. A music sheet having note perforations therein disposed in several lines lying 105 lengthwise of said sheet, and words disposed on said sheet with the transverse lines of the letters of the said words lying in similar direction one to another diagonally to the length of said sheet.

2. A music sheet having note perforations therein disposed in several lines lying lengthwise of said sheet, and words on said sheet having the order of the letters of each word lying diagonally to the length of said sheet, the order of the said letters of the said words being in similar direction. 70
3. A music sheet having note perforations therein disposed in several lines lying lengthwise of said sheet, and syllables on said sheet having the order of the letters of each syllable lying diagonally to the length of said sheet, the order of the letters of all the said syllables being in similar direction. 75
4. A music sheet having note perforations therein disposed in several lines lying lengthwise of said sheet, and words arranged in several rows thereon, each said row lying diagonally to the length of said sheet, the letters of each said row lying in one alinement. 80
5. A music sheet having note perforations therein disposed in several lines lying lengthwise of said sheet, and word syllables arranged in several rows thereon, each said row lying diagonally to the length of said sheet, the letters of each said row lying in one alinement. 85
6. A music sheet having note perforations therein disposed in several lines lying lengthwise of said sheet, and words arranged in several series on said sheet, each said series lying diagonally to the length of said sheet, and all said series diagonals being of similar direction one to the other. 90
7. A music sheet having note perforations therein disposed in several lines lying lengthwise of said sheet, and words arranged in several series on said sheet, each said series lying diagonally to the length of said sheet, all said series diagonals being of similar directions, the letters of each said series lying in one alinement. 95
8. A music sheet having note perforations therein disposed in several lines lying lengthwise of said sheet, and words arranged in several rows thereon, each said row lying diagonally to the length of said sheet, the first word of each such row positioned forwardly of the sheet in direction of its length, and the sets of words of every said row leading from left to right. 100
9. A music sheet having note perforations therein disposed in several lines lying lengthwise of said sheet, and words arranged in several series on said sheet, each said series lying diagonally to the length of said sheet, the first word of each such series positioned forwardly of the sheet in direction of its length, and the words of every said series reading from left to right. 110
10. A music sheet having note perforations therein disposed in several lines lying lengthwise of said sheet, and words arranged in several rows thereon, each said row lying diagonally to the length of said sheet, the first word of each such row positioned forwardly of the sheet in direction of its length, and the words of every said series reading from left to right. 115
11. A music sheet having note perforations therein disposed in several lines lying lengthwise of said sheet, and words arranged in several series on said sheet, each said series lying diagonally to the length of said sheet, the first word of each such series positioned forwardly of the sheet in direction of its intended line of travel, and the words of every said series reading from left to right. 120
12. A music sheet having note perforations therein disposed in several lines lying lengthwise of said sheet, and words arranged in several rows thereon, each and every said row lying diagonally to the length of said sheet, the first word of each and every such row positioned forwardly of the sheet in direction of its intended line of travel, said line of travel being downward, said words reading from left to right, and all said diagonal rows lying in similar direction. 125
13. A music sheet having note perforations therein disposed in several lines lying lengthwise of said sheet, and words arranged in several series on said sheet, each said series lying diagonally to the length of said sheet, the first word of each such series positioned forwardly of the sheet in direction of its intended line of travel, said line of travel being downward, said words reading from left to right, and all said diagonal series lying in similar direction. 130
14. A music sheet having note perforations therein disposed in several lines lying lengthwise of said sheet, and words arranged in several diagonal series on said sheet, all said diagonals being from left to right as to the grammatic sequence of the first and last words of each said series, and said diagonals being independent of any diagonal sequence of the said perforations. 135
15. A music sheet having note perforations of melody notes and accompaniment notes, the perforations of the melody notes being of different style than the perforations of the accompaniment notes, and the syllables and words of the melody arranged on said sheet, each said syllable or word transversely alined with its corresponding melody note perforations. 140
16. A music sheet for automatic musical instruments having note apertures therein, and words of a song printed on said sheet and extending transversely thereof at an oblique angle. 145
17. A music sheet for automatic musical instruments having note apertures therein, and words of a song printed on said sheet and extending transversely thereof at an oblique angle with a point of the first letter of each word or word syllable coinciding 150

with the leading end of the perforated notes corresponding to said word or word syllable.

18. A music sheet for automatic musical instruments having note apertures therein, and words of a song printed on said sheet and extending transversely thereof at an oblique angle with the lowest point of the first letter of each word or word syllable coinciding with the leading end of the perforated notes corresponding to said word or word syllable.

19. A music sheet for automatic musical instruments having note apertures therein and words of a song printed on said sheet at an angle inclined to the horizontal and ¹⁵ reading from the left to the right in an upward direction.
